[57] CLAIM

The ornamental design for a inflatable orthopedic pillow, as shown and described.

DESCRIPTION

FIG. 1 is a top plan view of an inflatable orthopedic pillow showing my new design;

FIG. 2 is a front elevational view thereof;

FIG. 3 is a rear elevational view thereof;

FIG. 4 is a bottom plan view thereof;

FIG. 5 is a right side elevational view thereof, the undisclosed left side being a mirror image of that shown; and FIG. 6 is a top, front, and right side perspective view thereof.

FIG. 1

FIG. 5

FIG. 2

FIG. 6

FIG. 3

FIG. 4
